UNITED STATES PATENT OFFICE

JOHN G. WEMPLE, OF ALBANY, NEW YORK, ASSIGNOR TO GENERAL ELECTRIC COMPANY, A CORPORATION OF NEW YORK

DESIGN FOR A COMBINED CLOCK, THERMOMETER AND THERMOSTAT

Application filed July 24, 1931. Serial No. 40,667. Term of patent 14 years.

To all whom it may concern:

Be it known that I, JOHN G. WEMPLE, a citizen of the United States, residing at Albany, in the county of Albany, State of New York, have invented a new, original, and ornamental Design for a Combined Clock, Thermometer and Thermostat, of which the following is a specification, reference being had to the accompanying drawing, forming a part thereof.

The figure is a front perspective view of a combined clock, thermometer and thermostat, showing my new design.

I claim:

The ornamental design for a combined clock, thermometer and thermostat substantially as shown.

In witness whereof, I have hereunto set my hand.

JOHN G. WEMPLE.
